UNITED STATES PATENT OFFICE.

FRANK M. STEINER AND GOTTFRID OLSON, OF MINNEAPOLIS, MINNESOTA, AS
SIGNORS TO STEINER SALES COMPANY, OF SALT LAKE CITY, UTAH, A CORPOR-
ATION OF UTAH.

TOWEL CABINET.

Application filed August 2, 1926. Serial No. 126,597.

Our invention relates to cabinets for dispensing or delivering a clean towel, a clean roll or web of the towel being placed in one part of the cabinet with a portion of the web 5 positioned where it can be grasped by the user and drawn out of the cabinet to a point convenient for use. The person using the towel is generally in a hurry and drops the web when he is through with it. The 10 soiled web when released may drop down outside of the cabinet and after a time may form a soiled loop outside the cabinet, trail on the floor and present an unsightly and untidy appearance.

15 The object of our present invention, therefore, is to provide means for positively and automatically drawing the soiled web of towel into the cabinet as soon as it is released by the user.

20 Other objects of the invention will appear from the following detailed description.

The invention consists generally in various constructions and combinations all as hereinafter described and generally pointed 25 out in the claims.

In the accompanying drawings forming part of this specification,

Figure 1 is a vertical sectional view through a towel cabinet embodying our invention;

Figure 2 is a horizontal sectional view on the line 2—2 of Figure 1.

In the drawings, 2 represents an upright towel cabinet having suitable legs 3 to rest upon the floor and provided with a compartment 4 adapted to receive a roll or web of clean towel 5. This is inserted through a door 6 in the side wall of the cabinet. The clean towel compartment is preferably divided horizontally by a shelf 7 to form a chamber 8 in which a reserve roll or web of towel may be placed. The clean web of towel is carried upwardly through an opening 9 in the rear of the cabinet and in contact with a wall 10 which extends preferably to a point near the top of the cabinet. The top is closed by a wall 11 and beneath this wall is a feed roll 12, a space or passage 13 being provided between the roll and the top wall through which the clean towel may be fed. 15 is a towel feed control device operated by a lever 16. An opening 17 is provided in the front of the cabinet between the closed top and the front wall and this opening is at 55 a suitable height from the floor to enable the

towel user to grasp the web and draw it outwardly to a point where the towel can be conveniently used. A second feed roll 18 has a driving connection as indicated by dotted lines, with the feed roll 12 and a takeup roll 19 is mounted to slide vertically in slots 20 and the soiled end of the towel is wound on this takeup roll and the roll rests by gravity in contact with the feed roll 18, which with the roll 12 has a sanded or roughened surface 60 so that when the roll 18 is revolved, a corresponding movement will be imparted to the takeup roll 19 to wind the soiled towel thereon.

When the towel is released by the user, there 70 is a tendency for it to drop down on the outside of the cabinet, and form a depending soiled loop and present an unsightly appearance, and continued use of the towel only aggravates this condition as the user 75 will not usually stop to gather up the loose web and push it through the opening into the cabinet and the janitor or other person in attendance is not always around to give the soiled towel attention when it should receive 80 it. We have, therefore, devised means for 85 automatically pulling the soiled web of the towel into the cabinet just as soon as it is released by the user, this means being set or made operative by the act of the user in drawing the clean towel out of the cabinet to a point where he can conveniently use it.

Referring to Figure 1 of the drawing, we have shown a yoke 21 of any suitable material, here illustrated as composed of a metallic rod bent to a suitable form and having its ends pivotally supported at 22 on the rear wall 10 of the cabinet, preferably above and near the chambers for the clean roll. The soiled towel web is passed around the cross-bar of this yoke and the weight of the yoke 90 normally causes it to assume the position shown in Figure 1 drawing the towel web taut as illustrated. When the user grasps the towel web and draws it outwardly 95 through the opening to the position indicated by dotted lines in Figure 1, the yoke will be raised to the dotted line position shown in Figure 1 allowing the web of towel to be drawn freely through the opening in the 100 front of the cabinet and the yoke will be retained in its raised position while the user is grasping the towel web, but as soon as he releases the towel web, the weight of the yoke 105 will immediately cause it to return to its nor- 110

mal position as indicated by full lines in Figure 1, drawing the soiled web of towel into the cabinet to a point where it cannot be seen from the front of the cabinet and 5 cannot present an untidy appearance in the toilet room or other place where the cabinet may be located. It will be understood of course, that we may not rely entirely upon the force of gravity to return the yoke to its 10 normal position as spring devices may be utilized in connection with the yoke, tending to force it downwardly and hold it in its depressed position.

As plainly shown in Figure 1, a plate 23 15 is pivoted at 24 above the take-up roll and having a downwardly curved forward portion for contact with the towel web, and limited in its downward movement by a stop 25. This plate acts as a guide to hold the 20 web of soiled towel forwardly to direct it downwardly and prevent it from interfering with the operation of the take-up roll.

The act of pulling the clean web out of the 25 cabinet will draw the towel over the upper feed roll and the frictional contact of the towel with this roll will cause the roll to be revolved and transmit its motion to the second feed roll to operate the takeup roll and wind the soiled web of towel thereon.

30 We claim as our invention:

1. A towel cabinet having a portion adapted to receive a supply of clean towel, a feed roll in the upper portion of the cabinet over which the web of clean towel is stretched, the 35 front of the cabinet adjacent said feed roll having a delivery opening through which the user may reach and grasp the web of clean towel and draw it outwardly from the cabinet, a second feed roll mounted in said 40 cabinet and having a driving connection with said first named roll, a take-up roll around which the web of soiled towel is wound for

contact with said second feed roll, and a yoke pivoted at the rear of the cabinet and having a crossbar engaging the web of soiled 45 towel, said yoke being raised when the user draws the web of clean towel outwardly through said delivery opening, and said yoke returning by gravity to its normal position and drawing the web of clean towel into the 50 cabinet when it is released by the user.

2. A towel cabinet having a support there- 55 in for a supply of clean towel, a feed roll in the upper portion of the cabinet over which the web of clean towel is stretched, the front 60 of the cabinet adjacent said feed roll having a delivery opening through which the user may reach and grasp the web of clean towel, a second feed roll mounted in said cabinet below said opening and having a driving con- 65 nection with said first named roll, a take- up roll arranged to contact with said second feed roll and around which the web of soiled 70 towel is wound for contact with said second feed roll, a plate hinged above said take-up roll and having a forward portion adapted to contact with the towel web and press the same outwardly toward said opening, a yoke 75 U shaped substantially in form pivoted at the rear of said casing below said second feed roll and having a bar around which the web of soiled towel is stretched to said take-up roll, said yoke normally tending by gravity to drop down within said cabinet and draw the web of towel backwardly through the opening in the front of said cabinet after it has been pulled out by the user and against the forward portion of said plate to be guided downwardly thereby.

In witness whereof, we have hereunto set 80 our hands this 29th day of July, 1926.

FRANK M. STEINER.
GOTTFRID OLSON.
